US00D847337S

(12) **United States Design Patent** (10) **Patent No.:** **US D847,337 S**
Fahl (45) **Date of Patent:** **** Apr. 30, 2019**

(54) **INSERTION AID FOR VOICE PROSTHESIS**

(71) Applicant: **Andreas Fahl**
Medizintechnik—Vertrieb GmbH,
Cologne (DE)

(72) Inventor: **Andreas Fahl**, Köln (DE)

(73) Assignee: **Andreas Fahl**
Medizintechnik—Vertrieb GmbH,
Cologne (DE)

(**) Term: **15 Years**

(21) Appl. No.: **29/614,434**

(22) Filed: **Aug. 18, 2017**

(30) **Foreign Application Priority Data**

Feb. 22, 2017 (EP) 003762129-0002
